PLYWOOD PRESS LOADERS

Robert A. Muller, New London, N. H., assignor to Atlas Plywood Corporation, Boston, Mass., a corporation of Massachusetts

Application June 16, 1951, Serial No. 231,998

11 Claims. (Cl. 144—281)

This invention relates to the manufacture of plywood panels and to a combination plywood press and press loading apparatus by means of which plywood materials may be more efficiently and economically handled and produced in relatively large scale operations.

The general process of producing such panels includes the steps of assembling the desired number of sheets of veneer cut to size in superimposed relation, certain surfaces of the sheets being coated with glue or other adhesive, and the sheets being arranged in the desired manner to produce an individual panel. These operations are repeated and a series of the panels are usually placed in a press loading mechanism which is designed to simultaneously feed the panels into a plywood press.

In carrying out such operations it is found to be highly important to protect the panels from exposure to heat prematurely in order to avoid an inferior quality product. Trouble in this way has developed in the past from having the loading apparatus too close to the press where considerable heat is maintained. A flow of heat from the press may, for example, either directly affect forwardly exposed portions of the glue coated panels, causing a precure, or the loader plates may become excessively heated, producing somewhat the same result.

To avoid exposure to heat and to allow time to properly stack plies, prior art devices of which I am aware have required that the press loading apparatus be provided as a separate unit which can be moved toward and away from the front of the plywood press during loading operations. From their very nature these prior art loading mechanisms are necessarily cumbersome to handle and thus involve a loss of valuable time. Moreover, they are complicated and very expensive to build and maintain and all of these factors have been found to undesirably increase the cost of manufacture of the plywood panels.

The present invention aims to deal with the problems indicated and to devise a combination plywood press and press loading structure with a view to providing a simpler construction; one which will be much less expensive to manufacture; more economical to operate; and one which, at the same time, will afford a degree of flexibility and safety in operation not present in prior art constructions.

These and other objects and novel features will be more fully understood and appreciated from the following description of a preferred embodiment of the invention selected for purposes of illustration and shown in the accompanying drawings, in which

Fig. 1 is an isometric view of the combination plywood press and press loader construction of the invention;

Fig. 2 is a fragmentary view, in vertical section, illustrating details of the press and loader feeding mechanism, and further showing a heat barrier member in one position of adjustment therein;

Fig. 3 is a fragmentary sectional view, somewhat similar to Fig. 2, but further illustrating the heat barrier member in another position of adjustment which it assumes in the feeding cycle;

Fig. 4 is a fragmentary sectional view corresponding to

2

Figs. 2 and 3, illustrating still a third position assumed by the heat barrier member in the course of a press loading operation;

Fig. 5 is a view, mainly in vertical cross-section, illustrating feeding mechanism for the press loader section of the apparatus of the invention;

Fig. 6 is a sectional view taken approximately on the line 6—6 of Fig. 5;

Fig. 7 is a perspective view further illustrating details of the panel feeding mechanism shown in Fig. 5;

Fig. 8 is a cross-section taken on the line 8—8 of Fig. 5;

Fig. 9 is a sectional view of one of the lugs used on the chains for driving the straps that operate the panel pushing bars;

Fig. 10 is a diagrammatic view showing the combination press loader and press mechanism of the invention as viewed from one side thereof and further indicating means for raising and lowering the heat barrier member shown in Figs. 2, 3 and 4;

Fig. 11 is another diagrammatic view of the apparatus shown in Fig. 10 and further indicating electrical control means associated therewith;

Fig. 12 is a diagrammatic view of the apparatus shown in Figs. 10 and 11, and further indicating a car for conveying plies of material into proximity to the loader;

Fig. 13 is a plan view of the operating mechanism for the chains above referred to;

Fig. 14 is a front elevation of said operating mechanism; and

Fig. 15 is a diagrammatic view of the wiring utilized in operating the present device.

The improved loader and press combination of the invention is based upon the novel concept of arranging a loader mechanism in juxtaposition to the front side of a press and securing this loader mechanism in fixed relationship to the press so that the loader becomes an integral part of the press, and the practice of moving the loader mechanism toward and away from the press is completely eliminated with much saving in time and labor being realized.

In thus locating a loader mechanism in relatively close proximity to the press, it is necessary to maintain the press loader plates relatively cool and, to do this, I provide a narrow space between the plates and the press and I combine with the press and attached loader mechanism a heat barrier member adjustably disposed in the space indicated between these two members in a position to thermally isolate the press loader mechanism, when this is desired.

Also in securing together the press and loader mechanism, and in providing means for thermally shielding the loader mechanism, certain other problems arise in connection with actually feeding the panels of plywood from the press mechanism into the press itself. I have devised a special form of feeding mechanism which is arranged in such cooperative relationship with respect to the press loader and heat barrier mechanism, that both a forward and return travel of the mechanism can be carried out without interference with the standard type of press construction.

The press mechanism with which the loader unit is used may be any one of several forms available commercially. A typical construction is shown in Pat. No. 2,420,813, granted May 30, 1947. These presses are constructed and operated as described in said patent and comprise a series of plates or platens arranged, one above another, with stepped supports for holding the plates in properly spaced relationship when the press is open for the introduction of panels between the plates. An hydraulically operated plunger positioned underneath the series of plates is operated at the desired time to lift the plates successively

off their supports, and finally to press them together with the force necessary to apply the desired degree of pressure to the plywood panels interposed between adjacent plates. The platens or plates are heated and usually the adhesive between the sheets of veneer is of a nature which requires curing so that suitable pressure and heat is applied to effect the desired chemical change in the adhesive material. A few of the plates of such a press are shown in Figs. 1, 2, 3 and 4 and are denoted by the numeral 2.

A typical arrangement by means of which panels are brought up to the combination press and loading mechanism, has been shown diagrammatically in Fig. 12, the press being indicated by numeral 3; the loader indicated generally by numeral 4; and a car indicated by numeral 5 mounted on tracks 6. The car brings the stacks of plywood assemblies to the loader where they are placed, either automatically or by hand, into the shelves of the loader and are later transferred simultaneously to the press 3.

Considering in greater detail the preferred embodiment of the invention shown in the drawings, the loader construction comprises a steel frame in which a series of shelves are mounted. The shelves may be of any suitable type and, as shown, consist simply of flat metal sheets 7 supported on brackets consisting of angle irons 9 which, in turn, are mounted on corner uprights 8. While the size of the shelves may be made to suit the requirements of individual situations, typical dimensions of shelves which have been successfully used are widths of 3 to 4 feet and lengths of 6 to 8 feet.

In accordance with the invention I locate the above described loader frame in juxtaposition to the front of the press 3 such that a relatively narrow space or vertical well is left between these units, and I solidly secure the loader frame in fixed relationship to the press in some suitable manner. I may resort to welding or I may bolt the two units either directly to one another, or I may employ other means. For example, in the preferred form of the invention shown in the drawings I provide a pair of vertical channel members, one of which has been shown in Fig. 1 and denoted by the letter U. One side of the channel member U is welded to an adjacent corner 8 of the loader frame, and an opposite side of the channel U is secured to an adjacent surface of the press 3.

With this channel arrangement a relatively narrow space is left between the units, as may be more clearly seen from an inspection of Figs. 2 to 4, inclusive, and in this space I have mounted a heat barrier member H consisting of a rigid sheet of insulating material, such as aluminum or some other suitable substance. The member H is slidably received in the two channel members U in a position such that it may be raised or lowered. To carry out the latter function I provide a winch or pulley arrangement P operated from an electrical motor M mounted on a support fixed above the loader frame, as suggested in Fig. 10.

When the heat barrier member H is in a fully lowered position in the channel members a very substantial thermal shielding effect can be realized, and I find that by using a thickness of aluminum of approximately three-eighths of an inch, for example, I am enabled to interrupt flow of heat from the press to the sheets of plywood in the loader sufficiently to avoid any danger of prematurely curing the glue-coating at the front edges of the plies, and the temperature of the metal sheets 7 can be constantly maintained at a satisfactorily low level.

It will be apparent that by loading the plies into the loader mechanism in such close proximity to the press, it becomes possible to carry out a much more efficient transfer of sheets from the loader frame to the press with a material saving in time, as well as complete elimination of any likelihood of over-curing the front edges of the plies.

In addition to these novel results, however, I find that I am able to realize still other unexpected benefits of an

important nature. Thus, in conventional types of loaders, it is now necessary for workmen, in the course of the loading operation, to stop at some point and move to a position in back of the loader where the inner edges of the plies may be inspected in order to make sure that they do not extend too far inwardly and are arranged in proper alignment with one another for delivery to the press.

In actual practical application of the heat barrier arrangement of the invention, it turns out that the need for checking is eliminated since the heat barrier H in its lowered position can be made use of as an alignment or register elements which operates to prevent the plies from being advanced too far forwardly during the loading operation. As a result a very appreciable speeding up of this part of the handling operation is realized and in the course of repeated loading cycles such faster handling necessarily becomes highly advantageous from an economic standpoint.

The heat barrier member H also has the virtue of introducing certain desirable safety features into the press loading operation. It is often found to be the case that workmen may be inadvertently fail to accurately check the register or alignment of front edges of the plies after they have been delivered from conventional types of press loaders. If the press in this condition is operated, as sometimes happens, with some of the plies out of register, there may occur both a waste of stock and also possible damage to the loading equipment with a loss of time.

In this connection it is pointed out that by properly using the heat barrier H of the invention, all plies will have been advanced forwardly into the press beyond a point where interference can take place, and must be so in order for the heat barrier member to be lowered into its bottom position.

To take the fullest possible advantage of this situation, I have also provided suitable limit switch means for controlling the operation of the loading and press mechanisms so that the movement of the hydraulic ram of the press into a raised position cannot occur until the barrier H is in a fully lowered position.

Thus, one arrangement for accomplishing this result has been illustrated in Fig. 11 where a normally open switch S1 is connected into the starting circuit for the motor M. This switch also controls operation of the loader mechanism through the motor 32, as will be hereinafter described. The connection of limit switch S1 is such that it holds open the circuit until the switch is closed by arrival of the barrier H in its top or fully raised position.

Another normally open limit switch S2 is arranged to be closed by movement of the barrier H into its fully lowered position and this switch is connected to the starter of the press so that the operation of closing the press cannot be started until after the door has been closed.

The safety feature thus realized will readily be apparent, and in actual practice it has been found that this safety feature results in very substantial savings in the cost and maintenance of the equipment taken over a period of time.

Attention is further directed to the feeding mechanism of the invention, and in this connection also to the fact that an essential requirement in a loader feeding mechanism is that all of the plies should be advanced into the press at substantially the same time in order to ensure uniformity of treatment of the plies. In prior art devices of which I am aware such an operation has been accomplished by means of pusher bars. These bars are driven through the aid of horizontally spaced-apart sprocket gears and chains engaging the gears. Each pusher bar requires a separate set of sprocket gears and chains capable of being reversed in direction.

Such an arrangement is necessarily of complicated and cumbersome character and, moreover, is not practical for use with a construction in which the loader is fixed in juxtaposition to the press, such as set forth in the present invention.

tion, owing to the fact that it is not feasible to mount sprocket gears and chain drive mechanisms directly on the press. One problem arises particularly. It is desirable in operating the press loader to push the feed bars well beyond the loader plates and completely into the press openings for a little distance, in any event, and in some cases all the way through these openings. Obviously sprockets and chains of prior art devices have definite limitations as to how far the pusher bars can be advanced when the loader is secured in juxtaposition to the press.

In the present invention I have devised a novel feed mechanism for a loader controlled by the limit switch S1 above referred to and especially designed to function with the combination of a press loader secured in juxtaposition to the press and having a movable heat barrier member adjustably disposed between them. By making use of compression type feed elements I am able to produce a forward movement of pusher bars without resorting to a horizontal sprocket chain drive and this movement is not limited in its length of stroke to any particular point in the press openings.

The novel feed mechanism of the invention has been shown in greater detail in Figs. 1, 5, 6, 7 and 8. As noted above, the shelves 7 of the loader are supported on angle irons 9 at the front section of the frame. In addition, I have provided a set of brackets 9', Figs. 2 to 4, inclusive, located at the back of the loader where they support the rearward edges of the shelves 7. Also associated with the brackets 9 and 9' are guide plates 10 which are located along two opposite sides of the loader frame adjacent to each set of shelves 7 in position to limit any endwise movement of the assemblies of veneer sheets.

It is pointed out that these assemblies come to the loader in the form of what may be termed "panels," each consisting of sheets of veneer, the number of sheets being usually between two and five. These assemblies have been produced following the coating of the proper surfaces of the sheets with adhesive so that after the pressing operation has been completed the desired number of plies in each panel will be secured firmly together. However, when the panels are brought to the loader, as for example, on the car 5, the plies for each panel are loosely assembled, but each panel is independent of its neighbor. If the operation of placing them in the shelves of the loader is to be performed by hand, then they are picked up, one or two at a time, by two workmen working together at opposite ends of the loader, each panel being slid edgewise in between the shelves.

Mounted in cooperating relationship with the guide plates 10 above respective shelves 7 are a plurality of feed elements or so-called "pusher bars" 11. Each one of these bars may conveniently consist of a strip of sheet metal folded into the form best shown in Figs. 5, such that the pusher bar presents an upright face *a* directed rearwardly to engage the plywood panels and an inclined front face *b*. In Fig. 1 only the inclined faces of the pusher bars appear, but the fact that they extend the entire length of the shelves is there illustrated.

To move the pusher bars back and forth across their respective shelves, I have combined with them individual driving elements, each of which acts somewhat in the nature of a rack capable of operating as a rigid member in compression in one direction of pusher bar travel and capable of functioning as a flexible member in tension in an opposite direction of pusher bar travel.

These driving elements comprise a plurality of resilient metal tapes 12, each of which has secured to one side thereof an extremity of a respective pusher bar by means of a fastening 12a, as shown in Fig. 5. The extreme end of each tape, however, preferably extends forwardly somewhat beyond the pusher bar, as indicated at *c* in Fig. 5. Also provided is a driving unit for each strap 12, comprising a wheel 13 provided with lugs *d* spaced around the outer periphery of the wheel to center and extend

through correspondingly formed holes in the tapes 12. Cooperating with each wheel and tape element is a press roll 14 which bears on the tape and holds the tape firmly against the wheel 13 so that no buckling at this point can take place. The press roll 14 has its central portion recessed to form an annular channel which permits passage of the lugs *d* therethrough as the tape element moves forwardly.

10 A vertical series of these wheels and press rolls are mounted on the outer sides of both of the corner standards 8, Fig. 1, the nature of the mounting being more clearly illustrated in Fig. 6. Each wheel 13 is secured fast on a shaft 15, Fig. 6, supported in bearings mounted in the frame piece 8. This shaft also supports another sprocket wheel 16 at the outer side of the frame piece 8. The press roll 14 is mounted on a stationary shaft 17, Fig. 6.

Referring to Fig. 1, it will be seen that all of the sprockets 16 at the end of the loader nearest the observer are arranged to mesh with a sprocket chain 18 which is supported on upper and lower sprocket wheels 20 and 21. Between adjacent sprockets 16 guide sprockets 22 are mounted to hold the chain in driving engagement with the sprockets 16.

20 The same arrangement is provided at the opposite end of the frame. Consequently, if the two sprocket chains are driven in unison, all of the rolls 13 which mesh directly with the straps 12 will also be driven in unison and, consequently, all of the feed bars 11 will be forced in the direction of the press across the shelves simultaneously and will push the plywood panels in contact with them through the loader and into the press at the same time. Fig. 5 shows these bars in full lines in one position assumed during their feeding movement.

25 While this movement is transmitted to each feed bar 35 by a thrust exerted lengthwise of that section of the strap 12 between the rolls 13 and 14 and the bar, the strap is so supported that it is not allowed to buckle and, consequently, the bars are operated positively. Referring to Figs. 5 and 8 it will be observed that the guide plate 10 40 is one flange of an angle iron, the horizontal flange 10' of which is riveted to the edge of the shelf 7 but is spaced from that shelf by a thin metal strip 23, slightly thicker than the strap 12. Consequently, more than half of the width of this strap is confined, closely but slidably, between the shelf 7 and the plate 10', and it therefore is compelled to transmit the thrust imparted to it by the rolls 13 and 14 by compression.

When the motion of the driving sprocket 16 is reversed, all the feed bars 11 are moved simultaneously 50 forward across the shelves to their initial positions at the front of the press, but the force applied through each pair of rolls 13 and 14 to its respective strap 12 is, at this time, a pull instead of a push. The free end portions of the straps are guided down through holes 34-34, Fig. 5, 1, in one of the base frame members and into suitable chutes or casing members in the floor below. Figs. 2, 3 and 4 illustrate several different feeding positions assumed by one of the pusher bars in the course of one feeding cycle.

60 At the front of the loader an angle plate 24, best shown in Fig. 5, extends along the entire front edge of each shelf where it assists in guiding the plywood sheets down on to the shelves as they are introduced into the space between adjacent shelves. Also, at the rearward end of 65 each shelf another angular plate 25 is secured to it by means of an angle bar 26 where it deflects downward any forward edge of a panel which may be curled or sprung upwardly.

The primary driving mechanism for the feed bars 11 70 is best shown in Figs. 13 and 14. It comprises a shaft 27 mounted on the top of the frame of the loader and carrying the two sprocket wheels 20-20 for driving the chains 18 at the opposite ends of the frame. This shaft is connected by two sprocket and chain drives 28-28 to the output shaft of a gear reduction unit 30 which, in

turn, is driven through its shaft connection 31 with the electric motor 32. Thus both sprocket chains 18 are compelled to revolve in unison. The shaft 29, Fig. 1, connects the two sprocket wheels 21 at the opposite ends of the frame.

It should be observed that the loader and the press are secured together in fixed relationship to each other so that the upper surface of each shelf is always in alignment with the upper surface of its cooperating press platen or plate 2 when the press is in its open position. While the platens are moved out of this relationship the shelves of the loader remain in permanently fixed positions, and the shelves of the press always return to their registering relationship with the shelves of the loader every time that the press is fully opened.

An outstanding advantage of the tape driving elements is that they can be satisfactorily combined with a press and loader mechanism secured in fixed juxtaposition to one another with the tapes mounted in such cooperative relationship to these members that transfer of plies from the loader to the press can be carried out without interference with the heat barrier H which must necessarily be moved in and out of the space between the loader and press during the loading cycle. This freedom from interference is made possible by reason of the fact that the tapes can operate in compression in one direction and in tension in the opposite direction. Because they can operate in compression during the feed stroke they can be supplied with a driving force which is exerted from a point well in back of the press and, consequently, there is no interference between the press and the driving mechanism.

On the other hand, the feed mechanism is not limited in its extent of travel and can readily enter into the openings between the press plies and, moreover, can actually feed all the way through the openings, if desired. Because of this flexibility and greater range of operation the pusher bars may, if desired, be used to eject pressed panels from the press before starting a new cycle. It will be apparent that the flexibility of the tapes allows them to be flexed at points where they leave the front of the press loader frame and thus may be guided downwardly in vertical overlapping relation to one another through the bottom slots in the frame out of the way of workmen when they are loading sheets into the front of the loader frame.

Control of the various operations of the machine is conveniently produced by electrical systems roughly similar to those used to control elevators and equipment of a like nature. This control may be such as to operate the loader automatically in accordance with a predetermined cycle, or the operation may be manually controlled. In the present instance this control system includes a switch 35, Fig. 1, provided with push buttons x, y, z, which operate through suitable relays to control the operation of the motor 32.

Assuming that the cycle is to be controlled manually, and that the loader has been filled, the operator presses the top button x which starts up the motor 32 in a direction to cause the feed bars 11 to move in the direction of the press, as above described, thus forcing the plywood panels in the loader into the press. When this transferring operation has proceeded to the desired point, it may be stopped by pressing the reverse button y, thus causing the motor to reverse its direction and, consequently, to return the feed bars to their initial positions at the front of the loader.

In an automatic cycle of operations the operator initiates the cycle by pressing the top button x, as above described, but when the push bars have completed their backward movement, a control lug 36 on the chain 18 strikes the operating arm of the lower limit switch 37. This closes the reversing switch, thus reversing the movement of the motor and, consequently, of the feed bars.

When they have returned to their initial positions at the front of the press, their movement is stopped by the engagement of the upper lug 38, Fig. 1, with the operating arm of the upper limit switch 40, which results in stopping the motor and completing the cycle. In this connection it may be pointed out that a reversal of the motor is accomplished through a zero-speed plugging switch 32', Fig. 13, driven from the shaft to the motor 32. Ordinarily these chain lugs and the limit switches are used because of the greater convenience and the saving in time which they afford.

It at any time during the cycle of automatic operations it is desired to stop the motion of the feed bars, the bottom button z should be pressed which will immediately stop the motor and the mechanism operated by it.

One of the lugs used on the chain is shown in detail in Fig. 9. It comprises a cam member A having upper and lower inclined surfaces to engage the operating element of either of the limit switches, a cooperating member B, and a screw C for securing these two parts to a link L of the chain 18. Consequently, the timing of the steps in the cycle controlled by these lugs can be changed by adjusting the lugs on the chain.

The straps 12 preferably are made of spring-type steel, although other materials obviously can be used, and the thickness should be so selected that they will operate, as above described. For the specific material mentioned, a thickness of in the neighborhood of .021 to .042 inch has proved satisfactory.

The components of the press loader mechanism described are subject to modification in various ways. For example, the barrier member, which has been described in the specification as being movable in a vertical plane by means of the hoisting mechanism indicated in the drawings, may also be arranged to move in other ways as, for example, in a horizontal direction, in which case the barrier might normally be disposed at one side or the other of the press loader mechanism. I may also desire to construct the door in sections, and in this connection I may provide a door made up of two sections split in the middle along a vertical line of separation with each section being arranged to move inwardly and outwardly from opposite sides of the loader frame.

It will be evident that combined loader and press apparatus made in accordance with this invention is relatively simple in construction and can be manufactured economically; it is also economical to operate; and has proved extremely reliable. A further advantage of these units is their unusual flexibility in operation. For example, such a machine will handle all sizes and shapes of plywood up to the maximum dimensions for which it is designed, which has been true of few, if any, prior art loaders of which I have been able to learn.

It will thus be seen that I have provided a press loader combining the features of a bendable rack or tape capable of transmitting compression or textile forces with a heat barrier member. I have further provided for the rack or tape rising in an essentially vertical path in front of the press loader mechanism, in this way providing for free access to the press loader for the operation of handling and loading plywood sheets from points in front of the loader. The tape after moving along a vertical path is so arranged that it changes its direction of travel and moves along a horizontal path. Presser bars are secured to individual tapes and in response to movement of the tapes are moved along a horizontal plane in both forward and rearward directions. The barrier member is so combined with the presser bars and bendable racks that it may act as a heat barrier to prevent precurving of plywood sheets and as a mechanical barrier to assure correct juxtaposition of the edges of the material to be loaded and pressed, thereby greatly reducing the possibility of production errors and eliminating the possibility of damage to the mechanism.

While I have herein shown and described a preferred embodiment of my invention, it will be evident that it may be embodied in other forms without departing from the spirit or scope thereof.

I claim:

1. In a plywood loader, in combination, a heated press assembly including a plurality of spaced plates arranged in superimposed relation, a loader rigidly fixed in side by side relation to the press and including a plurality of spaced shelves each in substantially the same plane as the adjacent press plate to permit the transfer of sheets of plywood from the shelves to a predetermined position on the adjacent press plates, said press plates and shelves having their adjacent marginal edges spaced to provide a well between the press and loader, a flat barrier structure supported above the well for vertical movement in said well between the press and loader to thermally insulate the loader from the press, and guide means for the barrier at each side of the well.

2. The structure according to claim 1, including means for moving the barrier vertically in said well and into and out of the path of movement of the plywood sheets; an electrical motor circuit including relay means for operating said press, and a switch in said circuit controlled by the position of the barrier for limiting the periods of operation of the press.

3. In combination, a plywood press, a loading apparatus fixed to and in spaced relation to the press, said press loading apparatus including a frame, a series of stationary shelves supported in said frame and adapted to receive sheets of plywood, a bar extending lengthwise of each of said shelves along the front edge thereof, two flexible driving members connected with opposite end portions of each of said bars, power driven mechanism operable through said flexible members to push said bars into the press to locate the sheets of plywood entirely within the press in substantially centered relationship therein, means at each side of each sheet overlying the flexible driving members to maintain same against buckling when operating to push said bars, a barrier movable into and out of the space between the press and loader, and means for synchronizing the movement between the barrier and the bar.

4. In a plywood loader, in combination, a heated press assembly including a plurality of spaced plates arranged in superimposed relation, a loader rigidly fixed in side by side relation to the press and including a plurality of spaced shelves each in substantially the same plane as the adjacent press plate to permit the transfer of sheets of plywood from the shelves to a predetermined position on the adjacent press plates, said press plates and shelves having their adjacent marginal edges spaced to provide a well between the press and loader, the spacing between each adjacent pair of plates and shelves being substantially the same, a flat barrier structure supported above the well for vertical movement in said well between the press and loader to thermally insulate the loader from the press, and guide means for the barrier at each side of the well, said guide means closing the vertical side of the well.

5. In a plywood loader, in combination, a heated press assembly including a plurality of spaced plates arranged in superimposed relation, a loader rigidly fixed in side by side relation to the press and including a plurality of spaced shelves each in substantially the same plane as the adjacent press plate to permit the transfer of sheets of plywood from the shelves to a predetermined position on the adjacent press plates, said press plates and shelves having their adjacent marginal edges spaced to provide a well between the press and loader, the spacing between

each adjacent pair of plates and shelves being substantially the same, a flat barrier structure supported above the well for vertical movement in said well between the press and loader to thermally insulate the loader from the press,

5 guide means for the barrier at each side of the well, said guide means closing the vertical sides of the well, bars lying transversely across each shelf, power driven flexible driving means for each bar, and guide means overlying the flexible driving means for preventing buckling during

10 operation.

6. The substance of claim 5 characterized in that the overlying guide means includes inner flat faces for engaging the side edges of plywood moving on said shelves.

7. A structure according to claim 1, including channel members for slidably supporting the heat barrier in substantially sealed relationship with respect to the front of the press, and means for vertically moving the heat barrier in to and out of the path of movement of the plywood sheets.

8. A structure as defined in claim 1, in which the heat barrier member comprises a rigid body adapted, in a closed position, to extend vertically between the frame and press in such close proximity to the edges of the said shelves as to constitute a stop for the plywood sheets.

9. A plywood press loader according to preceding claim 3, in which said flexible driving members are straps and said power driven mechanism includes two series of sprocket wheels positioned at opposite ends of said frame and meshing with the straps to drive them in one direction by pushing them and in the opposite direction by pulling them.

10. A plywood press loader according to preceding claim 3, in which said flexible driving members are straps, said machine including means defining guideways in which the respective straps run and the walls of which guideways support said straps against buckling during the periods in which they push said bars.

11. A press loader apparatus of the character described, comprising a frame, a bendable rack capable of transmitting compressive or tensile forces, said bendable rack being supported in the frame and adapted to move through a substantially vertical path at points externally of the frame and in close proximity thereto for the purpose of providing free access to the front of the loader frame, said bendable rack being constrained for movement through the frame along a horizontal path, pusher bars attached to the bendable rack and movable in response to said rack in both forward and rearward directions relatively to the frame, in combination with a flat plate like barrier 40 slidable to a position closely adjacent to the frame and movable with respect to the press loader frame to provide a heat barrier adapted to prevent precurving of plywood sheets in the press loader, said barrier member further functioning to assure correct juxtaposition of the edges of 45 the plywood sheets to be pressed.
